(57) **CLAIM**

The ornamental design for a tip of an attachment for the trailing end of a urethral drainage tube, as shown and described.

DESCRIPTION

FIG. 1 is a perspective view of a tip of an attachment for the trailing end of a urethral tube showing my new design;

FIG. 2 is a top plan view thereof;

FIG. 3 is a side elevational view thereof;

FIG. 4 is a side elevational view thereof;

FIG. 5 is a side elevational view thereof, opposite that shown in FIG. 4;

FIG. 6 is a perspective view thereof; and,

FIG. 7 is a top plan view thereof.

The broken line showing in FIGS. 1–7 of sections of an attachment for the trailing end of a urethral drainage tube and the drainage tube is for illustrative purposes only and forms no part of the claimed design.
